UNITED STATES PATENT OFFICE

WALTER L. DIXON, OF BOSTON, MASSACHUSETTS, ASSIGNOR TO REECE FOLDING MACHINE COMPANY, OF BOSTON, MASSACHUSETTS, A CORPORATION OF MAINE

FOLDING MACHINE

Application filed March 1, 1926. Serial No. 91,478.

This invention is a novel folding machine, that is, an apparatus for infolding cloth or analogous blanks. A particular object of the present invention is to afford such a machine which is capable of efficiently folding and pressing what may be described as a bellows fold, in the nature of a box pleat, sometimes desirable in pockets of jumpers, overalls or like garments, although the principles and features of the invention could be analogously used for various other articles. Other and further objects and advantages of the present invention will be pointed out in the hereinafter following description of an illustrative embodiment thereof or will be apparent to those conversant with the subject. To the attainment of the objects and advantages referred to the present invention consists in the novel folding machine, apparatus or mechanism, and the novel features of combination, arrangement, construction, mode of action and detail herein illustrated or described.

In the accompanying drawings, Fig. 1 is a left end elevation of a folding machine embodying the principles of the present invention, the illustrated machine being shown for convenience of the general type of the well known Reece folding machine illustrated, for example, in patents of Dixon, 956,950, granted May 3, 1910, or Reece, 972,916, granted October 18, 1910, although the features of invention could be embodied in very different types of machine. It is to be understood that the prior patents may be referred to for various matters of construction and detail not specifically involved in the present invention nor particularly described herein.

Fig. 2 is a front elevation of the machine shown in Fig. 1. In this figure as in Fig. 1 the parts are shown in their initial position, with the die or templet elevated above the bed, and the infolders retracted outwardly.

Fig. 3 is a top plan view of the machine shown in Figs. 1 and 2 with however the templet lowered upon the bed of the machine.

Fig. 4 is a section view taken on the line 4—4 of Fig. 3, looking from the left, and on an enlarged scale.

Fig. 5 is a central vertical section of the

templet as shown in Fig. 4, looking from the front, that is from the right side of Fig. 4.

Fig. 6 shows the original cloth piece or blank cut to shape and with the defining part of the templet in position thereon. 55

Fig. 7 is a view similar to Fig. 6, but after the opposite infolds or tucks have been formed over the defining edges of the templet, this view also indicating in dotted lines the extracted position of the templet. 60

Fig. 8 is a diagrammatic cross section taken on the line 8—8 of Fig. 7 showing the opposite folds or tucks formed in the fabric, while occupied by the templet and engaged by the infolders and resting upon the supporting bed or raised pad. 65

Fig. 9 is a view corresponding to Fig. 8 after the extraction of the templet.

Fig. 10 is a similar view after the withdrawal of the infolders. 70

Fig. 11 is a similar view showing the pressing elements in operation squeezing the folded blanks against the bed immediately after the withdrawal of the templet and infolders. 75

Fig. 12 is a face view of the article after the described infolding and after the intended infolding of the peripheral edges, thus producing a folded blank for what is known as a bellows pocket or expandible pocket 80 ready for attachment to jumpers or other articles of wear.

For convenience the description may be begun with the mode of procedure or successive steps in the folding operation. The original blank 15 shown in Fig. 6 is of the approximate shape of the finished article but sufficiently larger in all directions to allow for the infolding.

In the first stage of operation, indicated in Figs. 7 and 8, the longitudinal central portion of the blank is clamped down by the templet upon the bed while portions of the fabric to the front and rear are folded or tucked in, forming front and rear flaps 16, the result being indicated in Figs. 9 and 10, Fig. 11 indicating the material flattened or compacted under increasing pressure. 90

The product at this stage contains only the bellows fold or box pleat, and the infolding of the margins may be performed on various 100

types of Reece folding machines already known. For example, as shown in Fig. 12, the front and rear side margins 17 may first be folded in, then the diagonal or corner margins 18 and finally the long end margin 19 and the short end margin 20, including the previously tucked or pleated portion thereof. The marginal infolding is preferably done in a separate machine from the central or bellows folding of the fabric, although with a proper combination of mechanisms it might be performed in the same machine.

Before discussing the mechanism of the machine it may be convenient first to refer to those parts which directly contact the blank during the folding operations. Thus the raised bed portion or pad 22 directly supports the central portion of the blank which is to be infolded. The defining or thin portion or plate 23 of the templet is indicated as located directly above the supporting pad 22 but of slightly less dimension. The opposite or front and rear infolders 24 consist of thin straight plates mounted and operated as will be described. In addition to these parts Fig. 11 indicates a pressing means consisting of a pair of pressing elements 25 bearing downwardly upon the folds of the blank to squeeze them against the supporting pad 22.

The general machine parts may be briefly described as follows. The frame 30 is a rigid structure having supporting legs extending to the floor and horizontal parts on which the bed is supported and various projections and other formations as will be described. The horizontal portion of the frame gives rigid support to the table 31 of the machine, upon which is secured directly the supporting pad or bed 22. The frame is shown as having the usual rearward and upward extensions or brackets 33 in which is journaled the axle or rock shaft 34 about which the templet swings in descending to the bed and lifting therefrom; but as stated the general features may vary and the templet might be of the well known cross-head type sliding downwardly and upwardly. Power may be derived from a power shaft 35 having fast and loose pulleys at the rear end and with a driving worm 36 near the front end engaging a worm wheel 37 mounted directly on the main or cam shaft 38.

The templet 40 as a whole comprises working mechanism to be described, with the thin defining plate 23 at the lower side. This entire element is carried at the forward end of a pair of swinging arms 41 which are arranged to turn on or with the shaft or axle 34 so as to permit the upward and downward movements of the swinging templet. These movements may be effected through a rear extension 42 of one of the carrying arms, the same connected by a link 43, adjustable in length, to a lever arm 44 which is in the form

of a bell crank having an upwardly extending arm 45 at the extremity of which is a cam roll 46 bearing against the periphery of a cam 47 on the main or cam shaft 38. The weight of the templet holds the roll to the cam, and the contour is indicated in dotted lines in Fig. 1, showing that the templet is held elevated for nearly a quarter turn and then lowered quickly to the bed where it remains for near a half turn before being elevated to initial position.

The structure of the templet is well shown in the enlarged Figs. 4 and 5 in connection with the other views. The carrying arms 41 directly support the templet frame 49, which may be a hollow structure. Attached below this element is the templet body 50 which is of extended length and is formed at its underside with a track or guideway 51 in which travels longitudinally in a right or left direction the T-shaped stock 52 which at its lower edge has attached to it the templet defining plate 23. The templet stock 52 is confined in the guide slot by opposite bearing bars 53 which may be secured in any suitable manner, for example, by being clamped in place as shown by the pressure elements or blocks 25 attached by bolts to the underside of the templet body 50 near its middle. By this arrangement the defining plate 23 may be brought down in its defining or normal position as indicated in Figs. 3 to 5, and after the folding is adapted to be slid longitudinally toward the right to remove it from the folds, the T-shape stock guided by the tracks 51 and confining bars 53.

The templet has certain attachments, for example small lugs 55 extending lengthwise from each end of the body 50, these serving to make connection with the pressure applying mechanism for the purpose of pulling the presser blocks 25 down upon the work, as will be described. Another attachment is a spring pressed finger 56 adapted normally to occupy a small notch 57 formed at the middle of the left end of the templet plate 23, the stock 52 being slightly shorter than the plate at this end as clearly seen in Figs. 5 and 6. The finger 56 is carried at the end of a spring lever 58, thrown downwardly by its spring and having a tail which is adapted to be thrown at will by an eccentric latch 59 to hold the finger 56 elevated out of the notch 57. The operation of these parts will be described later.

There will now be described the means for retracting the defining plate 23 from the folds 16 by sliding it longitudinally toward the right, which movement as will be clear from Fig. 5, will carry the defining plate beyond the raised pad 22 so that the templet as a whole may descend slightly further to enable the operation of the presser mechanism. As already explained the defining plate 23 is attached at the bottom of the T-shape stock

52 which slides in ways 51 in the templet body 50. Mounted on top of the body 50 is shown an operating wheel 60 adapted to be turned to cause the rightward sliding of the templet stock and plate. The wheel or disk 60 turns freely about a stationary post or sleeve 61 which in turn is secured in place by an upright headed bolt 62. When the wheel is turned a half revolution it operates through 10 a link 63 to slide the templet stock 52 toward the right. The link 63 is connected to the leftward side of the disk or wheel through an upright sleeve or post 64 held in position by a headed bolt 65 which may be adjusted 15 radially along a slot 66 formed in the disk. The other end of the link 63 is connected by an upright post or sleeve 67 with the stock 52, there being a headed bolt 68 by which the sleeve is secured to the upper side of the 20 stock. These parts extend through a slot 69 formed in the body 50 and the bolt passes through a slot 70 formed at the upper side of the stock 52, the head of the bolt entering an undercut recess 71 formed in the stock. By 25 this arrangement a half turn of the disk 60 throws the stock and defining plate clear to the right, while a reverse movement restores them to normal, the disk 60 being in effect an adjustable crank arm.

30 These longitudinal movements of the templet plate may be effected through a pinion 74 attached to the underside of the disk 60, the pinion shown as being engaged by a rack 75 which is mounted at the forward end of an operating arm 76. While this arm might swing it is preferably arranged to slide rightward and leftward to operate the rack and for this purpose the rear end of the arm is secured to a portion of a sleeve 77 fitted to slide 40 loosely longitudinally on the rear axle 84. The slide 77 is provided with a pair of flanges 78 confining between them a ring 79 having outstanding pins 80 engaged by a yoke 81 formed at the upper end of a swinging arm 82. The lower end of the arm 82 is fulcrumed to a special bracket 83; and an intermediate portion of the arm is provided with a forwardly extending axle 84 carrying at its front end a cam roller 85 engaging in the 45 groove of a cam 86 mounted on the main shaft 38. By this arrangement the operation of the cam causes the swinging of the arm 82 and thereby the right and left sliding of the sleeve 77 and the operation of the rack 75 to rotate the disk 60 and effect the desired movements of the templet plate. The retracting movement of course is performed while the templet is down and after the folding but before the pressing operation, the cam 86 being 50 timed accordingly, and the restoring movement of the templet being timed to occur after all the operations are through and the templet has been elevated from the blank.

The infolding operation is performed by 55 the infolders proper or thin plates 24 which are moved toward each other from the front and rear sides so as to force the fabric in over the defining templet plate 23, the presser blocks 25 cooperating in this movement by holding the body of the fabric in place as the infolders thrust the fabric between the blocks and the templet. In this sense the blocks 25 are upper shaping members taking part in shaping the folds. The lower part of the templet stock 52 may also take part in the shaping action in the sense that it forms a stop or limit to the inward movement of the infolders. The five elements, the pad, the defining plate, the stock, the infolders and the overhanging shaping members thus cooperate to give entire control of the disposition of all parts of the fabric, insuring an accurate result.

Each infolder plate 24 is attached at the inner edge of a heavy member or stock 90, and the projecting portion of the infolder is preferably of such extent that as it comes to the limit of its inward movement the stock 90 abuts against the raised bed or pad 22, thus preventing any part of the fold extending outwardly beyond the defining plate itself. The length of the inner edge of each infolder stock 90 may be of the full extent of the edge to be infolded; but the outer end thereof may be narrowed to form a shank 91, as shown, 95 these parts being confined and guided in a box-like structure comprising a lower portion 93 and an upper portion or plate 94, the latter being held down by a number of small screws as seen in Fig. 3 and confining the infolder stock shank 91 in a slideway or recess formed at the upper side of the part 93.

The infolder guide boxes may be mounted as follows. Each of the lower portions 93 is shown pivoted at both sides upon upstanding stationary lugs 95. Standing outwardly from each lug is shown a spring wire 96 arranged to press upwardly on the outer part of the guide, thus throwing down the inner part thereof, while a set screw 97 is employed 105 for accurately adjusting the height of each infolder with relation to the supporting pad and templet. For the purpose of throwing the infolders inwardly and outwardly each stock 91 is shown provided with a downwardly extending lug or bracket 98, these being pivotally engaged and actuated by levers 99 having pin-and-slot connections 100 to the lugs. Each lever 99 is mounted on a counter shaft 101 to which is also adjustably secured 110 a cam lever 102 having at its lower end a stud or roll 103 entering a groove 104 of a cam 105 mounted on the main shaft 38. The contour of the cam is seen in Fig. 4 and it is so timed as to throw the infolders inwardly 115 after the templet is in place and draw them outwardly before the pressure operation. On the top of each of the infolder guide boxes are shown a number of work gages 107 arranged to position a blank of the form shown 120 125 130

in Fig. 6 so as to center it properly before the folding operation.

The necessary pressure may be applied by the following means. The endwise extending lugs 55 on the body of the templet have already been mentioned, and the downwardly extending pressure blocks 25, the feet of which overlie the fabric folds. By thrusting down on the lugs 55 pressure can be applied to the fabric. For this purpose there are shown a pair of opposite pressure hooks or latches 110. These are normally retracted and are so shown in Figs. 2 and 3. Fig. 1 shows one of them in end view. Each latch is formed with a front recess 111 to receive a control finger to be mentioned. The two pressure hooks are adapted to be swung inwardly to operative position and for this purpose each of them is pivoted to a slide bar 112 running in a slideway 113 at the corresponding end of the machine. The lower end of the slide bar is shown as provided with a pin and block connection 114 by which it is operatively connected to the slotted arm 115 of a bell crank lever, the downward arm 116 of which is provided with a cam roll 117 entering the cam groove 118 of a disk 119 on the main shaft 38. The cams 118 are so formed that the lever arms 116 will be thrown rearwardly and the hooks 110 pulled downwardly to cause the pressing operation at a time after the folds have been formed and after the templet and infolds have been withdrawn from the folds. In order to render the pressure hooks operative and inoperative at the proper times each of them is provided with a controlling finger 121 which engages in the recess 111. Each finger is mounted on a rock shaft 122 and is thus able to rock toward the right or left so as to move the pressure hook into or out of position. Each rock shaft is provided with a rearwardly extending arm 123 at its lower end having a cam roll 124 engaging a cam groove 125 in the periphery of the disk 119. The timing is such that the pressure hooks will be moved inwardly over the pressure lugs before the pressure is applied and will be moved away therefrom after the pressure has been relaxed and before the templet commences to rise.

The spring finger 56 operates to prevent slippage of the blank on the bed while the defining plate of the templet is sliding out of contact with the blank. As seen in Fig. 1 the spring finger normally projects below the templet plate, and it therefore contacts lightly upon the blank and holds it pressed down upon the bed while the templet comes into position. The spring lever 58 yields during this action leaving the parts in the position shown in Fig. 5. When the templet is slid out lengthwise after the folding, the finger remains in position and holds the blank so that it cannot be drawn out with the

templet. The eccentric 59 can be used to regulate the amount of play of the finger.

The preferred operation has been indicated, but may be recapitulated as follows: Figs. 1 and 2 show the elements of the machine in normal or original position. The operator will position the blank with relation to the gages 107 and shift the power belt or otherwise start the main shaft, turning preferably for a single rotation. The templet descends quickly and is positioned accurately upon the blank as indicated in Figs. 3, 4, 5 and 6, operated from the cam 47. The infolders then move inwardly operated by cams 104, to the position indicated in Figs. 7 and 8. The folds are thus formed between the bed, the templet, the infolders and the overlying shapers or blocks 25. The templet plate or stock, is then shifted bodily to the right to the position indicated by dotted lines in Fig. 7, operated by cam 86, leaving the parts as shown in Fig. 9. As the templet plate passes from over the raised pad 22 the entire templet drops slightly until the blocks 25 come directly upon the folds. The infolders are then moved outwardly by their cams to the position indicated in Fig. 10. The pressure hooks having been moved inwardly by cams 125 are now drawn downwardly by cams 118 giving forcible squeezing and creasing of the folds as indicated in Fig. 11. After the relaxing of the pressure the pressure hooks are moved outwardly and the templet starts upwardly, its defining plate thereafter sliding leftward toward its normal position so that at the end of a complete rotation of the main shaft the parts are all restored to normal position.

It will thus be seen that there has been described a folding machine embodying the principles and attaining the objects and advantages of the present invention. Since many matters of combination, arrangement, construction, mode of action and detail may be variously modified without departing from the underlying principles it is not intended to limit the invention to such matters except so far as set forth in the appended claims.

What is claimed is:

1. A folding machine for producing bellows or box folds or pleats in cloth or other blanks, having in combination a bed, a templet having opposite defining edges for the respective folds, a carrier therefor adapted to move toward and from the bed, means for shifting the templet to retract it longitudinally out of the enclosing folds, an overhanging shaping member spaced above the defining member, infolders adapted to thrust the material over the edges of the templet and thus form reverse folds between the bed and shaping member, and means for squeezing the folds after the retraction of the templet and infolders.

2. A folding machine as in claim 1 and

wherein the templet shifting means operates to slide the templet longitudinally its full length to remove it from the blank.

3. A machine for producing bellows or box

5 folds or pleats in cloth or other blanks, having in combination a defining member having opposite defining edges for the respective folds, a carrier therefor adapted to move toward and from the bed, a raised bed of approximately the length and width of the defining member, arranged to support the blank during folding, infolders adapted to thrust the material over the edges of the defining member and thus form reverse folds, 70 means for shifting the defining member to retract its longitudinally out of the enclosing folds, and beyond the end of the raised bed, an overhanging member spaced above the defining member adapted to drop upon 75 the folds upon the retraction of the templet 80 from over the bed, and means for squeezing the folds between the overhanging member and bed after the retraction of the defining member and infolders.

25 4. A machine for producing open ended box pleats in cloth or other blanks, comprising a bed, a templet with straight opposite longitudinal defining edges, a templet carrier adapted to move toward and from the bed, means for longitudinally shifting the templet bodily to retract it out of an end of the enclosing folds, an overhanging shaping member supported by said carrier at each side and spaced above the templet, straight 90 infolding means at each side of the templet 95 adapted to thrust the material of the blanks over each side edge of the templet and thus form at each side reverse folds between the bed and the shaping member, the shaping member at each side being of such width as to cover both of the folds formed at that side, and means for squeezing the two folds at each side consisting of mechanism adapted to force the overhanging shaping member 100 relatively towards the bed.

5. A machine for producing bellows or box folds or pleats in cloth or other blanks, having in combination a defining member having opposite defining edges for the respective folds, a carrier therefor adapted to move toward and from the bed, shaping members carried by said carrier and spaced slightly above said defining edges, opposite infolders arranged to thrust the material between the 105 shaping member and defining edges to form reverse folds, a blank supporting pad, means for shifting the defining member to retract it longitudinally out of the enclosing folds, and from above the raised pad, and thus 110 to permit the shaping members to drop upon the folds, and means for squeezing the folds between the shaping members and pad after the retraction of the defining member and infolders.

65 6. In a machine for producing bellows or

box folds or pleats in cloth or other blanks, the combination of a raised bed, a templet having a central stock and opposite defining edges for the respective folds, a carrier therefor adapted to move toward and from the bed, means for shifting the stock to retract the edges longitudinally out of the enclosing folds, an overhanging shaping member spaced above the defining edges, infolders adapted to thrust the material over the edges of the defining member and thus form reverse folds between the bed and shaping member, each infolder comprising a plate portion adapted substantially to meet said stock and a stock portion adapted substantially to meet said bed, in the inward movements thereof.

7. In a machine for producing bellows or box folds or pleats in cloth or other blanks, the combination of a raised bed, a templet having a central stock and opposite defining edges for the respective folds, a carrier therefor adapted to move toward and from the bed, an overhanging shaping member, means for shifting the stock to retract the edges longitudinally out of the enclosing folds, 85 opposite infolders for forming reverse folds in the blank, a guide for each infolder, means pivoting each guide to allow up and down adjustment at its inner edge to adapt the infolder to advance between the templet and the shaping member, and adjusting means therefor.

8. In a machine for producing bellows or box folds or pleats in cloth or other blanks, the combination of a raised bed, a templet having a central stock and opposite defining edges for the respective folds, a carrier therefor adapted to move toward and from the bed, an overhanging shaping member, means for shifting the stock to retract the edges longitudinally out of the enclosing folds, opposite infolders for forming reverse folds in the blank, a guide for each infolder, means pivoting each guide to allow up and down adjustment at its inner edge to adapt the infolder to the bed and templet, and adjusting means therefor, consisting of a set screw fixing the elevation of the infolders, and a spring holding the guide thereto, and permitting yield.

9. A folding machine as in claim 1 and wherein the templet carrier is provided with a spring finger engaged in a recess in the defining edge of the templet, adapted to hold the blank upon the bed during the longitudinal shifting of the templet.

In testimony whereof, I have affixed my signature hereto.

WALTER L. DIXON.
